DEPOSIT RECEPACLE

Filed March 28, 1928

UNITED STATES PATENT OFFICE

GEORGE COUGHLIN, OF NEW YORK, N. Y.

DEPOSIT RECEPTACLE

Application filed March 28, 1928. Serial No. 265,414.

This invention relates to deposit receptacles, more particularly to coin deposit receptacles generally known as "poor boxes". It has for its object to provide a receptacle of this character which can be easily and cheaply manufactured and can be so constructed as to prevent unauthorized access to the interior of the receptacle or any illicit removal of the coins deposited.

10 A further object of the invention is to provide a receptacle of this nature which can be so secured in position as to prevent removal of the receptacle itself except by authorized persons.

15 With these and other objects in view, my invention will be more readily understood by referring to the accompanying drawings in which:

Fig. 1 is a longitudinal sectional view on 20 the line 1—1 of Fig. 2;

Fig. 2 is a longitudinal sectional view on the line 2—2 of Fig. 1, which view is taken at right angles to that of Fig. 1; and

25 Fig. 3 is a sectional plan view on line 3—3 of Fig. 1.

Upon referring to the drawings 1 designates the body of my receptacle which is preferably made from ordinary metal pipe of any suitable length and diameter. Secured at the top of the body portion or pipe 1 is a top plate 2 provided with a rearwardly extending portion 3 having the ears 4 provided with suitable openings 5 for the reception of fastening means 6 such as screws or the like for securing the receptacle in position. Top plate 1 is provided with a suitable coin slot 7 and depending from the top plate into the interior of the pipe 1 is a coin chute 8 which may be of any desired shape but preferably rectangular. Secured to the interior of the chute 8 are the downwardly inclined plates 9 which may be arranged in staggered relation. These plates 9 permit the ready downward passage of a coin through the chute and into the bottom of the pipe 1 and yet retard illicit withdrawal of the coins by means of a wire or any other instrument.

50 The plate 2 has a flange 10 embracing the upper end of the pipe 1 to which it is secured

by rivets or screws 11 thereby securing the top plate and the pipe together.

Intermediate the ends of the pipe 1 and beneath the delivery end of the coined chute 8 is provided a rotating or oscillating deflector 12 provided with the vanes 13. The deflector has suitable pintles or axes 14 disposed in openings on opposite sides of the pipe 1 so as to permit the deflector to oscillate on its axis. The deflector is further provided with an additional vane 15 which may serve as a counter-balance to normally maintain the deflector in the position shown.

The deflector being turnably mounted beneath the discharge end of the chute it will be seen that a coin dropping from the chute will hit one of the vanes of the deflector, turn the same and drop into the bottom of the receptacle. The deflector will aid in preventing the withdrawal of any coin by means of wire or any sticky substance on the end of an instrument of any kind. The side vanes of the deflector, by means of the counter balance, are always in close proximity to the walls of the pipe 1 as shown.

At the other or lower end of the pipe 1 is secured a bottom plate 16 similar in contour to plate 2 having at its rear the lugs 17 corresponding to the lugs 5 of the top plate and having openings 18 in which suitable fastening means 19 may be employed to hold the plate in position against a wall or the like. The plate is provided with an upstanding flange 20 embracing the lower end of the pipe 1 and is secured to the pipe by means of suitable fasteners 21 which may be screws, rivets or the like. The bottom plate 16 is provided with an opening 22 preferably circular in contour and has formed in the side walls a ledge 23. The opening in the plate 16 has a suitable closure 24 provided with a flange 25 engaging the ledge 23 so as to prevent inward movement of the closure. Carried by the closure on its inner surface is a lug 26 which engages behind the ledge 23 as shown in Figures 2 and 3. Also carried by the closure is a suitable locking mechanism 27 having the lock bolt 28 which engages behind the ledge 23 at a point preferably diametrically opposite the lug 26. The locking mechanism 27 is acces-

sible for manipulation from the outside of the closure by means of a suitable combination knob 29 or other operating means, such as a key or the like. By manipulating the knob 29 the bolt 28 may be moved back and forth to unlock or lock the closure in position.

In addition to the screws or fasteners 6 and 19 additional means may be provided for preventing theft or bodily removal of my improved deposit receptacle or poor box. My preferred form of securing means comprises providing in the pipe 1 at the rear thereof an elongated slot or opening 30 to receive a headed bolt 31 such as a L-headed bolt secured in a wall or other support. At the lower end of the receptacle 1 is provided a suitable opening 32 to receive a bolt 33 provided with an opening 34 at its free end to receive a locking pin 35 preferably of wedge or conical shape. The receptacle is first hooked over the bolt 31 which engages in the slot 30 with its L-head engaging the inner surface of the pipe 1. The weight of the receptacle will then cause the bolt 31 to become seated in the upper end of the slot 30 while the opening 32 is in alignment with the bolt 33 which extends into the receptacle. Then the locking pin 35 is applied in the opening 34.

30 My improved deposit receptacle is designed to fit closely to the walls or support to which it is attached and it will be seen that the body portion or pipe 1 is closely adjacent to the support so that access to the bolts 31 and 33 can be had only with great difficulty. To prevent these bolts from being cut or sawed or otherwise broken, I have provided blocks or plates 36 which may be secured to the body portion 1 in any suitable manner, such as welding, riveting or the like. These blocks or plates 36 are of substantially the same thickness as the flanges 10 and 20 of the top and bottom plates and are provided with openings corresponding in shape to the openings 30 and 32 with which they align. These blocks 36 cover up that portion of the bolts 31 and 32 which would be accessible to a saw because of the spaced relation to the body portion 1 of the wall or support by reason of the flanges 2 and 20.

I prefer to construct my improved deposit receptacle entirely of metal such for instance as cast steel or the like so that it will be strictly burglar proof.

55 While I have shown in the drawings the top and bottom plates 2 and 16 secured to the pipe 1 by means of fasteners such as screws, it is perfectly obvious that these plates can be suitably welded to the pipe 1 instead of using the screws. When the screws are employed they will be counter-sunk and filed down so as to be flush with the outer surfaces of the plates, thereby obscuring them from observation. If desired the whole receptacle 85 may be painted or otherwise coated so as to

prevent rust or wear and at the same time hide or cover up the fastening means.

What I claim is:

1. A deposit receptacle including a tubular body having end closures, the upper one of the end closures having a coin slot, a tube of less area than the tubular body integral with and suspended from the upper end closure, spaced from the wall of said tubular body and projecting into the body, said tube communicating with said slot and being provided with stationary internal baffles. 70

2. A deposit receptacle including a tubular body having end closures, the upper one of the end closures having a coin slot, a tube of less area than the tubular body rigidly united with and suspended from the upper end closure, spaced from the wall of said tubular body and projecting into the body, said tube communicating with said slot and being provided with stationary internal baffles, and a pivotally mounted deflector arranged within the tubular body below said tube, said deflector having an upwardly projecting fin and oppositely extending wings. 80

85 3. In a deposit receptacle, a tubular body having end closures, the upper end closure being provided with a coin slot, a baffled coin chute arranged in the body and of less diameter than the body, and a pivotally mounted deflector positioned in the body below the coin chute and including upwardly and downwardly extending fins, and laterally extending wings, said deflector being approximately of the same interior diameter as that of the 100 tubular body. 95

105 4. A deposit receptacle including a tubular body and end closures, each of said end closures including an endless flange embracing the outer surface of the tubular body, means engaging the flanges for permanently securing the end closures to the body, the upper end closure being provided with a coin slot and a depending coin chute, and the lower end closure including a port, and a lockable door 110 closing the port. 110

115 5. In a deposit receptacle, a tubular body provided with end closures, each of said end closures having a rearwardly projecting part provided with a plain outer surface to engage a supporting wall, screws projecting through the rear portion of the body, and metal protecting plates surrounding the screws and having their rear faces in substantially the same plane as the rear faces of the projecting portions of the end closures. 120

125 6. A deposit receptacle including a tubular metal body having metal end closures, each end closure having an annular flange snugly engaging and secured to the wall of the tubular body, the upper one of the end closures having a coin slot, a tube of less area than the tubular body integral with and suspended from the upper end closure, spaced from the wall of said tubular body and projecting into 130

the body, said tube being of substantially the same width as the length of the coin slot, and communicating with said slot, and stationary baffles projecting toward one another from opposite sides of the tube and having their ends overlapping.

7. A deposit receptacle to be supported against walls and the like, comprising a tubular body having end closures, the rear portion of said tubular body being provided with an elongated slot, rearwardly extending parts projecting from the end closures, an L-shaped screw extending through the elongated slot in the body portion and engaging the inner surface of the body portion, a port provided in the rear portion of the body below said slot, another screw passing through said port and having its head portion arranged within the body and provided with an eye, a wedge-shaped locking key engaging said eye from within the tubular body, and metallic washers secured to the body portion around the openings therein, said protecting washers being of the same thickness as the rearwardly projecting parts of the end closures where the latter engage the wall, the point of engagement with the wall of the projecting parts of the end closures, the bolts, the openings in the body and the protecting washers lying substantially in the same straight line.

In testimony whereof I affix my signature.
GEORGE COUGHLIN.
